CLARENCE H. WILEY, OF HARTFORD, CONNECTICUT.

INDEX.

1,089,890.

Specification of Letters Patent. Patented Mar. 10, 1914.

Application filed December 12, 1906. Serial No. 347,562.

To all whom it may concern:

Be it known that I, CLARENCE H. WILEY, a citizen of the United States, and a resident of Hartford, in the county of Hartford and State of Connecticut, have invented an Improvement in Indexes, of which the following is a specification.

My invention relates more especially to the class of devices used for ascertaining the location of matter in account or similar sheets, and the object of my invention is to provide simple and convenient means for locating such matter; and a further object of the invention is to provide an index that shall have a wide range as to the subject matter to be located; and a further object of the invention is to provide a structure in which the wear upon the index shall be reduced to a minimum.

20 An index in the use of which these objects may be attained is illustrated in the accompanying drawings, in which—

Figure 1 represents what may be termed sections of a ledger and showing the embodiment of my invention. Fig. 2 is a view of a portion of the pages of an account book showing a modified form of the invention. Fig. 3 is a view showing a modified form of index page. Fig. 4 is a view showing a different arrangement of the index characters.

For the purpose of simplifying the illustration and description of my invention I have shown only a portion of a book structure which would usually be employed, the invention being complete in each section, although several such sections may ordinarily be employed.

The numeral 5 denotes what I term a permanent index sheet, in that it is designed for retention in the book longer than other sheets or until worn out, and this sheet may be provided along one edge with indicating characters 6. In the preferred form of the invention the front or long edge of the sheet, is arranged for the reception of these indicating characters, although it will be obvious that the characters may be located along any edge.

50 A set of memoranda or account sheets 7, constituting temporary sheets and consisting of any suitable number, is located appurtenant to each permanent index sheet. These temporary account sheets are so formed outside of the edge of the permanent index sheet 5 that they may be selected by

means of indicating characters located or to be located on said permanent index sheet, the formation on each memoranda sheet being located for identification by means of a 60 special character or characters on said index sheet.

In the form shown herein the memoranda sheets are stepped from top to bottom along their front edge, a step on a sheet being located opposite a character on the permanent index sheet. If, as hereinbefore stated, the character on the permanent index sheet shall be located other than as shown, the formation of the edges of the memoranda sheets, 70 of course, will be correspondingly positioned.

A section indicating sheet 8 may be employed, and this may be suitably formed as with a tab 9, which may bear any suitable 75 character for the purpose of locating a section desired.

In carrying out my invention I contemplate that the characters may be supplied to the permanent indicating sheets 5 and that 80 the size of said sheets shall be with special reference to that of the memoranda sheets, and the latter shall have their edges formed so that they may be selected by means of characters which may be placed upon the 85 permanent index sheet, although, ordinarily such permanent index sheet will be provided with the proper characters as desired in the book when completed for sale.

In the form of device shown in Fig. 2 the 90 invention contemplates the use of two sets of characters 11 upon a permanent index sheet 10, and the memoranda sheets may be included in two sets 13 and 14, each set being selectively formed with reference to 95 characters at the edge of the permanent index sheet. From this it will be seen that a single permanent index sheet may be made to serve for a plural number of sets of memoranda sheets in a single section. In 100 this instance, as before, a section indicating sheet bearing a tab 25 may be employed for locating the different sections or sets of sections of this book. From this it will be seen that a section includes at least one permanent index sheet, one or more sets of memoranda sheets, and a section indicating sheet, the latter if desired. It will be seen further from this arrangement that the permanent index, by means of which the 110 memoranda leaves are located, is not touched in the operation of finding such

sheets, and that the life of such permanent index sheet is therefore greatly prolonged, as the characters will not become defaced or the sheet worn by constant handling, the wear coming on the selective formations of the temporary or memoranda sheets, which do not bear characters to become defaced.

The index may be used indefinitely and will outlast the continuous use of a large number of memoranda sheets, especially as the latter are frequently removed and replaced by other pages or sheets, so that they do not get continuous wear. In Fig. 3 of the drawings I have shown the section indicating tab 20 as attached to the indicating sheet or page 21. This form of section indicating means may be employed in some instances, in which case, of course, the section indicating sheet will be dispensed with.

In the use of the index shown in Fig. 1 the tabs 9 are employed to indicate a section. It being assumed that the upper tab designates section A it may bear that character, and will be used to locate the upper section of sheets as shown in this figure. The use of the section indicating sheet to indicate a section will bring to view the characters along the edge of the permanent index sheet, which indicate the second letter of the names in this section it being considered that the entire section contains names beginning with A. The top letter of the sub-column with the stepped page opposite said letter would locate the names beginning with Aa as "Aarons." The second would indicate Ab as "Abrams."

In the index shown in Fig. 2, the section indicating tab is used in the manner above described to indicate a section in which either all or a part only of the names may begin with A. The capital letters on the indicating sheet denote the second letter of the name, all names in which the second letter is between A and E being found on one of the stepped pages between those letters, and so on, the names with the second letter between E and H being found in the stepped pages between those letters. The small letters indicate the third letter of the name, all names in which the third letter is between a and l appears on one of the steps opposite a, those between l and r upon the steps opposite l and so on. The fourth letter of the name determines the exact page on which the name will be found. All names in which the fourth letter is between a and l being found upon the page bearing the inside row of steps; those between l and z on those bearing the outside row of steps.

In short the fourth letter of the name will determine the exact step and page upon which the name will occur, the small letters the horizontal rows of steps in which the name will be found, and the large letters a section of the indicating sheet opposite

which a page bearing the name will be found and the tab the section on which the name will be found. For instance the name "Abbe" being desired the tab will give the section beginning with A, the large letter A will indicate that the name will be found in the steps in the section between the letters A and E, all names in which the second letter is one of those between A and E being found in this part of the section. The small letter a will indicate that it will be found on one of the steps opposite that letter, all names in which the third letter is between a and k inclusive being so located. The fourth letter of the name (e) coming before l indicates that the name will be found on the page having the tab on the inner vertical row opposite the letter a.

In the form of device illustrated in Fig. 4 the section is located by means of a tab (designated by the numeral 15 in Fig. 4) as above set out and each section is composed of a plural number of sub-sections 16-17 similarly arranged to the sections 13-14 in Fig. 2. A sub-index sheet 18 is employed in connection with these sub-sections, the temporary index sheet 19 being provided for the whole section. This index sheet 19 is of a width equal to that of the under sub-section 16, and the sub-indicating sheet 18 lies with- 95 in the steps on the sub-section 16. The purpose of this arrangement is to allow various sub-divisions under a character indicating certain sections of a ledger. For instance the name "Smith" being one which frequently occurs, the section, covered by the initial letter "S" is opened, and then by the use of the step opposite the letter m on the main indicating sheet the sub-section in which the second letter m of the name occurs is located. In turning this sheet the sub-index sheet 18 is uncovered which governs all of the names having the first two letters "Sm". The memoranda sheet bearing the first or top step may contain all of 110 the names beginning with the two letters "Sm" with the exception of the name "Smith" and the other sheets thereunder may bear the name "Smith" and the letters A, B, C, etc., on a sub-index sheet may indicate the initial letter of the first name of the person "Smith".

I claim—

1. An index sheet designed to receive index characters, a set of memoranda sheets each having on its edge a selective formation relatively located with respect to and to be identified by a character on the index sheet, said formations on the memoranda sheets being blank and being located outside 125 of the edge of the index sheet.

2. An index sheet having characters extending along an edge, a set of memoranda sheets each having a selective formation on its edge relatively located with respect to 130

and to be identified by one of said characters on the index sheet, said formations being blank and located outside of the edge of the margin of the index sheet.

5 3. An index sheet designed to receive index characters, a set of memoranda sheets each having on its edge a selective formation relatively located with respect to and to be identified by a character on the index sheet, 10 and a section page provided with means located outside of the edges of the index sheet and memoranda sheets for locating the sections composed of said sheets.

4. An index sheet provided with characters extending along an edge, a set of memoranda sheets each having on its edge a selective formation relatively located with respect to and to be identified by one of said characters on the index sheet, said formations being located outside of the edge of the index sheet and being blank, and a separate section indicating page provided with means located outside of the edges of the other pages for locating a section composed of an 25 indicating sheet and memoranda sheets appurtenant thereto.

5. An index sheet designed to receive index characters, a set of memoranda sheets each having on its edge a selective formation relatively located with respect to and to be identified by a character on the index sheet, and means located outside of the edges of the index sheet and memoranda sheets for locating the section composed of said sheets.

35 6. An index including a permanent index sheet designed to receive index characters and a set of temporary memoranda sheets, each of the latter having on its edge a selective formation relatively located with respect to and to be identified by a character on the index sheet, and a permanent section indicating page provided with means located outside of the edges of the other pages of the section for locating said section, said 40 section indicating page being separately formed from the other pages or sheets of the section.

7. An index including a permanent index sheet, a section sheet bearing a tab to receive a character to denote a section, and a set of temporary memoranda sheets composing a section and sub-section, each sheet having a selective formation on its edge lo-

cated relatively to and to be identified by a character on said permanent index sheet.

55

8. A book including a sub-divided section and an index sheet arranged for permanent use therein, said index sheet having characters along its edge to denote subdivisions of the section governed by the index sheet, means located outside the edges of the index sheet said index sheet also having sub-characters to denote the character of the section and a set of temporary memoranda sheets each having its edge provided with selective formations each relatively located with respect to and to be identified by a sub-character on the index sheet, said formations being blank and located outside of the edge of said index sheet.

70

9. A book comprising a group or subdivision of leaves of uniform width cut away along one edge so as to expose portions of the faces of the leaves in stepped series, and a separate index leaf arranged on top of the 75 said group of leaves and of a size to be entirely within the superficial limits defined by the leaves of the said group and to leave exposed the cut away, stepped portions of the indexed leaves, the index leaf bearing 80 indexing characters in alphabetical arrangement and disposed close to that edge of the sheet which lies next to the exposed cut away parts of the leaves of the said group and respectively opposite the said exposed portions.

10. A book comprising a series of groups of sheets, the sheets of each group being cut away along one edge to expose portions of the faces thereof in a stepped series, an index for each group of sheets comprising a sheet of a size to be arranged entirely within the superficial limits of the indexed sheets and provided with a row of alphabetically arranged indexing characters in alinement 90 respectively with the exposed portions of the indexed sheets, the characters being close to the edge of the sheet and the said sheet being on top of the group for which it serves as an index, and a division sheet of distinctive character arranged immediately above each index sheet, substantially as set forth.
